UNITED STATES PATENT OFFICE.

HARRY S. HART, OF CHICAGO, ILLINOIS.

PLATE-METAL CAR END.

Application filed January 8, 1921. Serial No. 435,793.

To all whom it may concern:

Be it known that I, HARRY S. HART, a citizen of the United States, residing at Chicago, in the county of Cook and State 5 of Illinois, have invented certain new and useful Improvements in Plate-Metal Car Ends, of which the following is a specification.

This invention relates to an end for rail-way cars and is designed primarily for gondola cars, but it may be used on cars of other types.

The invention has for its object to provide a construction of car end which will 15 be self sustaining, particularly under loads which may be imposed thereon at points laterally remote from the place of suspension, thereby rendering relatively unimportant end sills or other heavy transverse load-sus- 20 taining members.

The invention proceeds upon the principle of incorporating in, and integrally with, the sheet or plate which forms the end wall of a car, stiffening ribs so disposed that a 25 load imposed vertically at one point in the end will be transmitted as strains of tension and compression to a point in the end laterally offset from the loading point and where the end will be provided with its 30 main vertical support. Preferably, and in the embodiments of the invention herein disclosed by way of illustration, the end receives its support at its middle point, as, for instance, upon a center sill or draft member, 35 and the metal end on either side of the vertical line of this center support is pressed between dies to form ribs leading diagonally from the vertical line of loading to the vertical line of main sustension, such diagonal 40 ribs serving either as tension or compression members, according to whether they are inclined from the middle downwardly and outwardly, or upwardly and outwardly, and additional ribs being disposed to coact there- 45 with in completing the truss as members of compression or tension as the case may be. Additional ribs or corrugations may be pressed into areas of the metal end which are not initially concerned in the primary 50 distribution of stresses which characterizes the invention, and these will serve mainly to stiffen the intermediate areas and render the end less vulnerable against impact in directions other than in the general plane of the 55 sheet.

In the accompanying drawings—

Figures 1 and 2 represent, in elevation, two car ends in which two embodiments of the present invention are, respectively, incorporated; and

Figure 3 is a modification of the form shown in Figure 2.

In Figure 1, 1 represents the end plate of a gondola car, and 2 the center sill of such a car. The plate 1 is pressed between 60 dies or otherwise formed or fashioned to provide ribs 3 extending diagonally from the respective sides of the plate to the center. In this form of plate, the diagonal ribs 3 extend downwardly and inwardly so 65 that loads imposed vertically upon the side marginal portions of the end plate will be transmitted inwardly through said ribs as stresses of compression. This distribution of stresses of compression will load the area 70 of the plate lying between said ribs with stresses of tension which will gradually decrease from the upper edge toward the meeting point or lower ends of the compression ribs. To adapt the plate to withstand 75 these strains of tension, a tension rib 4 is pressed into the upper portion of said area, and this terminates at a point sufficiently near the ribs 3 to strengthen the sheet against the stretching influence of the 80 vertical loads which the ribs 3 transmit. An additional rib or ribs 4^a may also be located in the area between the diagonal 85 ribs, if desired.

5 represents strengthening ribs which may 90 be disposed in any desired numbers in the areas between the compression ribs 3 and the lateral margins of the end plate.

According to Figure 2, the diagonal ribs 3^a extend from the upper central portion 95 of the end plate to the lower marginal portions thereof, so that vertical loads imposed on said marginal portions will be transmitted upwardly and inwardly to the center line of the plate as loads of tension. To 100 vertically sustain this central portion of the end plate, one or more compression ribs 6 are introduced so that the loads transmitted inwardly and upwardly by the tension ribs 3^a will be transmitted vertically to the center sill 2 by the compression member or members 6. If a plurality of vertical compression members are to be substituted for the member 6 in Figure 2, they will preferably be arranged as suggested at 6, 6^a, and 110

6^b in Figure 3. In Figures 2 and 3 the areas of the plate not immediately concerned with the transmission of its load, may be provided with stiffening ribs 5^a and 5^b.

- 5 From the foregoing description it will be seen that the end plate which will, of course, be attached at its margins to the usual angle iron or other framing of the car, will be adapted to transmit vertically imposed 10 marginal loads diagonally inward to the vertical center line of the plate, through the medium of diagonal ribs extending from the margins to said center line, and these ribs will be sustained by coacting members that 15 will combine therewith in the distribution of the stresses to form a complete truss. In Figure 1 the guide or transmitting ribs are located to serve as members of compression and the coacting truss members as members 20 of tension; whereas in Figures 2 and 3 the diagonal members serve as members of tension and their coacting member or members are under compression.

I claim:

- 25 1. In a railway car, a center sill, an end wall, said end wall being a one-piece member provided with ribs to transmit to said center sill downward forces applied adjacent to the sides of a car, said ribs including 30 diverging compression ribs extending from a point directly above said center sill to points at the upper corners of said end wall

and a horizontal tension rib lying intermediate of, but terminating short of the upper ends of said diverging ribs.

35

2. In a railway car, a center sill, an end wall, said end wall being a one-piece member provided with ribs to transmit to said center sill downward forces applied adjacent to the sides of said car, said ribs including diverging compression ribs extending from a point directly above said center sill to points at the upper corners of said end wall, and a horizontal tension rib lying intermediate of the upper ends of said diverging ribs.

45

3. A complete end wall for a railway car comprising a single integral, substantially rectangular plate, and a center sill supporting said plate, said end wall having a pair 50 of diagonally arranged ribs extending from points near the sides of said plate to a region over said center sill and another rib parallel with an edge of said plate for taking stresses set up in said diagonal ribs by forces remote from said center sill, said ribs constituting tension and compression members for directing forces remote from said center sill to a region above said center sill.

55

Signed at Chicago, Illinois, this 4th day of January, 1921.

HARRY S. HART.
